UNITED STATES PATENT OFFICE.

HARRY A. SPURGEON, ALVIN T. HUNT, AND WILLIAM G. BAKER, OF INDIANAPOLIS,
INDIANA.

RULE FOR TYPE-SLUGS.

1,139,594.

Specification of Letters Patent. Patented May 18, 1915.

Application filed July 20, 1914. Serial No. 851,929.

To all whom it may concern:

Be it known that we, HARRY A. SPURGEON, ALVIN T. HUNT, and WILLIAM G. BAKER, citizens of the United States, residing at 5 Indianapolis, Marion county, and State of Indiana, have invented and discovered certain new and useful Improvements in Rules for Type-Slugs, of which the following is a specification.

10 Our invention relates to rules for type slug forms and its object is to provide a table rule of a conformation that will enable it to be locked to the body of the slugs below the "quad high" surface thereof, to 15 be easily inserted and withdrawn and providing a portion projecting beyond such surface and having a printing edge level with the type faces.

With this object in view, our invention is 20 embodied in preferable form in the rule hereinafter described and illustrated in the accompanying drawings.

In these drawings, Figure 1 is a top plan view of a form showing the improved rule 25 applied thereto, Fig. 2, an end view of the form showing a type slug in side elevation and several rules in place, Fig. 3, an enlarged vertical section of the rule, Fig. 4, an enlarged side in elevation of part of a rule 30 and Fig. 5, an enlarged detail perspective of part of a slug and a rule.

Referring to the drawings, 1 indicates a cast type slug of a tabular type form arranged for printing a table of columns of 35 printed matter. For printing a vertical ruling line, of a table, it is usual to employ a rule extending from top to bottom of the form, between the ends of a slug. Our invention provides a construction of this rule 40 that may be firmly locked in the body of the type slug, and it is formed with a flat base 2, inwardly and upwardly inclined sides 3, extending from the base at acute angles thereto and a more acute rule edge forming 45 upper portion provided by the side faces 4, 4, which meet the side faces 3 at acute angles. The base 2 and side faces 3 thus form a truncated pyramid which constitutes the slug engaging portion of the rule, 50 and the height of the sides 3 is made equal to the depth of a slot 5 also preferably of truncated pyramidal shape which is formed in the body of the type slug below the level of the top of the body proper of the slug.

The slug from the body to this level is des- 55 ignated as "quad high" and this upper face may therefore be called the "quad high surface" or merely "quad surface". It is denoted by the numeral 6. The printing characters project beyond this surface. The 60 side faces project upwardly to a height level with the type faces of the slugs, thus providing the rule edge for printing the ruling line. These side faces are shown as meeting so as to form a comparatively sharp edge, 65 but of course a blunt or flat contact surface may be provided by changing the angles of the side faces 4.

In the use of the rule, a plurality of type 70 slugs having the slots 5 in alinement, are assembled and the rule inserted endwise at one end of the line of slots. The slug engaging portion of the rule formed by the base 1 and inclined sides 2 will fit against the base and walls of these slots, and will 75 be firmly locked against movement upward at a right angle to the face of the form owing to the inclination of the slot walls, and the greater width of the base of the rule as compared with the upper part of the slot 80 engaging portion, and this locking engagement will thus be obtained within the body of the slug itself, thereby avoiding the necessity of additional detachable rule holding means or of projections formed on the slugs 85 above the quad surface. The rule edge forming portion projects freely above the quad surface to "type high" level, leaving a clear space between the rule edge and the adjoining columns of printing characters, 90 and enabling such characters to be closely and properly spaced.

These table rules are customarily formed 95 of brass and are necessarily of small width in cross section relative to their length. In the form of table rule now employed, which rule is supported on the quad surface and hence must be of slight thickness and low height and its sides of substantially uniform inclination throughout to obtain the required sharp printing edge and also a gripping surface for the locking means on the slugs, the rule is pliable and easily bent.

In our invention, owing to the greater 105 angle of the side of the lower part of the rule, and the engagement therewith of the body of the slug below the quad surface, the rule is of sufficient lateral thickness to pro-

vide a stiff body which may be readily inserted in the slots and pushed through the same without bending.

Having thus described our invention,
5 what we claim is:

1. A rule for type slugs having a lower type slug engaging portion provided with an upwardly and inwardly inclined side face and a rule edge-forming upper portion 10 having a side face extending angularly to said face of said lower portion, substantially as described.
2. A rule for type slugs having a lower type slug engaging portion which is adapted 15 to extend below the quad surface and which has a base and sides inclined to the base, said rule having an upper portion adapted to extend above the quad surface and having side faces angularly joining the sides of said 20 lower portion, substantially as described.
3. A rule for type slugs having a portion adapted to engage the body of a type slug below the quad surface only and having a side face inclined inwardly from the base 25 upwardly, to engage a slot wall of the slug,

and said rule having an upper portion providing a rule edge and adapted to extend above the quad surface to the level of the type face, said upper portion having a side face meeting the side of the lower portion at 30 an acute angle, substantially as described.

4. A rule for type slugs having a lower type slug engaging portion in the form of a truncated pyramid and an upper portion 35 equal in height to that of the type faces having side faces joining the sides of the lower portion at acute angles and converging to form a ruling edge, substantially as described.

In witness whereof, we have hereunto set 40 our hands and seals at Indianapolis, Indiana, this 16th day of July, A. D., nineteen hundred and fourteen.

HARRY A. SPURGEON.
